Frank Ledermann

UNITED STATES PATENT OFFICE

JACOB MAUTHE, OF WATERBURY, CONNECTICUT

PENCIL FINGER SUPPORT

Application filed April 23, 1929. Serial No. 357,414.

The main object of this invention is to provide a device which may be slipped over the body of a pencil for the purpose of resiliently supporting the forefinger of the hand upon the pencil so that greater ease and comfort are had in writing.

Another object of this invention is to provide a device which will give greater ease to writers, and will prevent writer's cramp.

10 The above and other objects will become apparent in the description below, in which characters of reference refer to like-named parts in the drawing.

Referring briefly to the drawing, Figure 1 is a perspective view showing a pencil equipped with the finger support as held in the hand in writing position.

Figure 2 is a top plan view of the complete finger support blank, showing its shape before being formed.

Figure 3 is an end elevational view of the finger support.

Figure 4 is a top plan view of Figure 3.

Figure 5 is a longitudinal sectional elevational view of the finger support, showing the finger platform in normal position.

Referring in detail to the drawing, the numeral 10 indicates a blank of material which is spring brass or some other similar metal. 30 This blank 10 has a substantially circular area 11 blanked out of the remainder of the metal. The line of shearing between the blanked-out portion 11 and the member 12 is absent at one position so that this blanked-out portion 11 forms a unitary path with the blank 10. The blank 10, to the exclusion of the blanked-out portion 11, is formed into a sleeve 12 which is resilient and is adapted to have a pencil 13 inserted into its bore 14.

40 The marginal side edges of the blank 10 after being formed into a sleeve 12 are separated by a slit 15 which permits resilient fitting of the sleeve 12 to various sizes of pencils within a predetermined limit. The circular blanked-out portion 11 is negatively arched or curved concavely to form a saddle 16 upon which the forefinger 17 of the hand is adapted to rest when the hand is in a writing position. The saddle 16, from the position where it joins 50 the sleeve 12, inclines upwardly, and at its

outer free end is provided with a pair of ears 18 which have depressions 19 formed therein.

The device is adapted to be used as an aid in writing, and prevents the well-known writer's cramp. The sleeve 12, after the blank 55

10 illustrated in Figure 2 has been formed circularly, is slipped over the pencil 13 to its most desirable position along the length of the pencil 13. The tip of the forefinger 17

of the hand is then permitted to rest upon 60 the saddle 16 with the thumb 20 of the hand grasping the side of the pencil 13, as is usual in the writing position. The platform or saddle 16, on account of its being resiliently

attached to the sleeve 12, readily yields to the 65 pressure of the forefinger 17 upon the pencil 13 and permits greater ease in writing than would ordinarily be possible. The depressions 19 on the ears 18 receive the tip of the

forefinger 17 of the hand and prevent this 70 forefinger 17 from slipping from the saddle 16, which would possibly occur were these ears 18 not provided with the depressions 19.

It is to be noted that certain changes in form and construction may be made without departing from the spirit and scope of the invention.

I claim:

A finger support used in combination with a pencil comprising a slotted sleeve adapted 80 to slip over a pencil, an upwardly sloping concave saddle having part of its periphery integral with said sleeve, the free portion of said saddle being adapted to yieldably support the forefinger of the hand, prominences 85 extending from the upper free portion of said saddle and depressions in said prominences adapted to receive the tip of the forefinger for retaining said finger in natural position upon 90 said saddle.

In testimony whereof I affix my signature.
JACOB MAUTHE.
